LPA(57) **CLAIM**

The ornamental design for a “carafe lid,” as shown and described.

DESCRIPTION

FIG. 1 is a front view of the carafe lid, wherein the rear view, right side view and left side view are the same as the front view;

FIG. 2 is a slightly downward-looking front perspective view thereof;

FIG. 3 is a top view thereof; and,

FIG. 4 is a bottom view thereof.

The broken line areas showing portions of the carafe lid form no part of the claimed design.
